UNITED STATES PATENT OFFICE.

HENRY A. WEIHMAN, OF PHILADELPHIA, PENNSYLVANIA, ASSIGNOR TO JOHN F. SIMONS AND THOMAS MADDOCK, OF PHILADELPHIA, PENNSYLVANIA, FREDERICK M. SIMONS, OF SWARTHMORE, PENNSYLVANIA, AND EDWIN S. SIMONS, OF ORANGE, NEW JERSEY, COPARTNERS, TRADING AS SIMONS BROTHER & COMPANY, OF PHILADELPHIA, PENNSYLVANIA.

DESIGN FOR SUGAR-TONGS.

No. 38,383.

Specification for Design.

Patented Dec. 25, 1906.

Application filed November 7, 1906. Serial No. 342,426. Term of patent 7 years.

To all whom it may concern:

Be it known that I, HENRY A. WEIHMAN, of the city and county of Philadelphia, State of Pennsylvania, have invented a new, original, and ornamental Design for Sugar-Tongs, of which the following is a specification, reference being had to the accompanying drawings, forming part thereof.

In the drawings, Figure 1 is a front view,

and Fig. 2 is a back view, of a sugar-tongs, showing my new design.

I claim—

The ornamental design for sugar-tongs, as shown.

HENRY A. WEIHMAN.
